APPARATUS FOR PUTTING SLACK IN ANCHORING ASSEMBLIES OF ELECTRICAL CONDUCTORS

Ulrich C. Dunaway, St. Louis, and Firmin M. Cunningham, Maplewood, Mo., assignors to James R. Kearney Corporation, St. Louis, Mo., a corporation of Missouri

Application March 21, 1938, Serial No. 197,097

10. Claims. (Cl. 254—67)

This invention relates generally to an apparatus for imparting pull to electrical conductors supported by poles and the like for the purpose of putting slack in anchoring assemblies associated with said electrical conductors which anchoring assemblies include insulators, clamps, and other appurtenances usually employed as parts of such anchoring assemblies, the predominant object of the invention being to provide an apparatus of this type which is of relatively simple construction and arrangement and is capable of performing its intended function in a highly efficient manner.

Line anchoring assemblies of the type with which the improved apparatus disclosed herein may be used ordinarily comprise one or more strings of insulators, the insulators of each string of insulators being movably and removably connected together, and each string of insulators being connected at its opposite ends by suitable means to a pole or other support and to an associated electrical conductor. It frequently happens because of breakage, or for other reasons, that it becomes necessary to replace insulators or other parts of an anchoring assembly, and therefore provision must be made for temporarily attaching the electrical conductor to a pole or other support while the anchoring assembly is being disassembled in accomplishing the replacement of parts thereof. Also the means employed for temporarily attaching the electrical conductor to the pole or other support must be of such nature that the tension ordinarily present in anchoring assemblies because of the attachment of electrical conductors thereto may be relieved so that the anchoring assemblies may be disassembled for the purpose of replacing parts thereof.

The apparatus disclosed herein is of such improved construction and arrangement that the task of arranging it in place in assembled relation with respect to a pole, or other support, and an associated electrical conductor, is relatively simple and may be accomplished with maximum safety to the line-men performing the task, and also the improved apparatus includes means capable of simple and convenient operation for putting slack in the assembly with which it is associated so that said assembly may be disassembled to the extent necessary to replace parts thereof.

Fig. 1 is a plan view of the improved apparatus showing same as it appears when in use in association with a pole and an associated electrical conductor, parts of the apparatus being broken away.

Fig. 2 is a side elevation of the structure and

its arrangement illustrated in Fig. 1, parts of the apparatus and parts of the pole being broken away.

Fig. 3 is a cross-section taken on line 3—3 of Fig. 1 and looking in the direction indicated by arrows.

Fig. 4 is a cross-section taken on line 4—4 of Fig. 1 and looking in the direction indicated by arrows.

Fig. 5 is a fragmentary view partly in elevation and partly in vertical section illustrating the manner of attaching the apparatus to an electrical conductor.

Fig. 6 is a fragmentary plan view of the forward end portion of the apparatus which is attached to an associated electrical conductor.

Fig. 7 is a cross-section taken on line 7—7 of Fig. 1.

Fig. 8 illustrates the manner of using the improved apparatus in a vertical position.

In the drawings, wherein is shown for the purpose of illustration, merely, one embodiment of the invention A designates the apparatus generally. The apparatus A includes a pair of elongated bars 1 and 2 which are disposed in spaced, substantially parallel, relation as shown to good advantage in Fig. 1. The bars 1 and 2 are formed of wood, or other suitable electrical insulating material and at their rear ends the bars 1 and 2 have fixedly mounted thereon sleeves 3 and 4, each of said sleeves being provided with an end wall, at its outer end as shown at the bottom of Fig. 1. The end wall of each sleeve is spaced from the adjacent end of the associated bar and arranged in the space between said parts of each bar and sleeve assembly is the head of a bolt, the bolt associated with the bar and sleeve assembly 1—3 being designated by the reference character 5 and the bolt associated with the bar and sleeve assembly 2—4 being designated by the reference character 6. The shanks of the bolts 5 and 6 pass through openings in the end walls of the sleeves and said shanks, which are of substantial length, extend rearwardly from the rear end of the sleeves.

When the apparatus A is in use the shanks of the bolts 5 and 6 are disposed at opposite sides of a pole P, or like support, with which the apparatus is associated and said bolt shanks support a yoke 7, shown to the best advantage in Fig. 1. The yoke 7 is generally of arcuate shape and includes outwardly projected extensions 8 at its opposite ends, said extensions being provided with openings 9 formed therethrough which

are open at the end faces of the extensions. The shanks of the bolts 5 and 6 extend through the openings 9 formed in the extensions 8 of the yoke 7 and pins 10, which are arranged in apertures formed in portions of the extensions at opposite sides of the openings 9 thereof, serve to confine the shanks of the bolts in the inner portions of the openings 9. The rear face of each extension 8 of the yoke 7 is provided with a recess 11 in which is seated a ball bearing assembly 12 and the shank of each bolt 5 and 6 has mounted on the screwthreaded portion of the shank thereof a nut 13 which is adapted to be screwed into contact with a portion of the associated ball bearing assembly 12 (Fig. 1).

In order to properly support the yoke 7 relative to the pole P particularly while the apparatus is being arranged in place for use a strap 14 is arranged about the pole, said strap being provided with a suitable buckle 15 by means of which the strap may be fastened securely about the pole as shown in Fig. 1. Arranged in engagement with the pole-embracing strap 14 is a relatively short, vertically disposed strap 16. The upper portion 25 of the vertically disposed strap 16 embraces the pole-embracing strap 14 while the lower portion of said vertical strap engages an eye 17 associated with the yoke 7 so as to support said yoke relative to the pole P. The yoke 7 is provided with a centrally located portion 18 of substantial circular cross-section through which an opening is formed from front to back. A rod 19 is disposed in the opening of the portion 18, said rod being provided with a pointed forward portion 19' providing a spur which is adapted to be forced into the wood of the pole to assist in supporting the yoke in position on the pole. To secure the rod 19 in place a nut 20 is mounted on the screwthreaded rear end portion of said rod, said nut being adapted to engage the rear end face of the portion 18 of the yoke.

Adjacent to their forward ends the bars 1 and 2 are connected together by a cross member which includes an inner element 21 of upwardly curved formation as shown in Figs. 1, 3, and 6, said inner element being provided with opposed, substantially horizontal portions 21' provided each with a transversely curved cavity 21a formed therein in which one of the bars 1 or 2 is seated (see Fig. 3). When viewed in plan the opposed, substantially parallel end portions of the inner element 21 are elongated in the direction of the extension of the bars 1 and 2 (Fig. 1) and the transversely curved cavities 21' formed in said opposed end portions extend from front to back of said elongated portions.

In order to secure the inner element 21 to the bars 1 and 2 said inner element has associated with it a pair of opposed clamping members 22, each clamping member 22 being secured to the inner element 21 by a pair of U-bolts 23 and 24. The bridge portions of the U-bolts 23 pass about forwardly extended portions of the opposed end portions of the inner element 21, and the leg portions of said U-bolts 23 are extended through apertures formed in the clamping members 22 and have nuts mounted thereon. The U-bolts 24 have their bridge portions extended through openings formed in the opposite end portions of the inner element 21, and the leg portions of said U-bolts 24 likewise extended through apertures formed in the clamping members and have nuts mounted thereon. The clamping members are provided with cavities which extend from front to back thereof, the walls of said cavities

being curved in conformity with the cross-sectional curvature of the bars 1 and 2 so that portions of said bars may be received by said cavities. Also each of the clamping members is provided with a downwardly and rearwardly extended hook 25 which serves a purpose to be hereinafter set forth. It is plain that when the nuts are drawn up on the screwthreaded legs of the U-bolts 23 and 24 the bars 1 and 2 will be securely clamped between the opposed end portions of the inner element 21 and the clamping members 22 whereby said bars 1 and 2 will be connected together in a manner to maintain the transverse spacing thereof.

Formed in the opposed end portions of the inner element 21 are openings through which rod portions 26 extend, said rod portions being extended rearwardly beyond the opposed end portions of the inner element and nuts 27 being mounted on said extended rod portions for attaching the rod portions to said inner element. The forwardly extended portions of the rods of which the portions 26 form parts converge toward each other as indicated at 28 in Fig. 1, and at their forward ends the convergent rod portions 28 are attached to a member 29. The member 29 includes opposed sleeve portions 30 in which the forward end portions of the convergent rod portions 28 are secured, and intermediate of these sleeve portions the member 29 is shaped to provide a tapered opening 31 (see Figs. 1, 3, and 5). The tapered opening 31 of the member 29 terminates at its forward end in a vertical slot 32 formed in the forward portion of the member 29 (see Fig. 3) and at the bottom of the member 29 an opening leading into the tapered opening 31 is provided which is in the form of slot 33 that extends rearwardly from the lower end of the vertical slot 32 to the rear end of the member 29. Projected rearwardly of the member 29 are extensions 34 which are located at opposite sides of the opening 33.

The apparatus A includes a clamp 35 which is attached to an electrical conductor C on which pull is to be imparted with the aid of the apparatus. The clamp 35 includes a body portion 36 having an inclined lower wall 37 and provided with an opening 38 formed in a side thereof which extends from end to end of the clamp as shown in Fig. 5. The clamp 35 includes also a wedge 39 which is disposed within the body portion of the clamp with its inclined edge face 39' in contact with the inclined bottom wall of the body portion of the clamp. At its rearward end the wedge 39 is provided with a knob 40, and this knob together with an adjacent portion of the wedge have a notch 41 formed therein which is open at its top as shown in Fig. 3. When the apparatus A is in its normal operative position the knob 40 is disposed in the tapered opening 31 of the member 29 as shown in Fig. 5.

Supported in positions below the bars 1 and 2 is a pair of similar bars 42 and 43 which like the bars 1 and 2 are formed of wood or other suitable electrical insulating material. At points adjacent to their forward ends the bars 42 and 43 are connected together and are suspended from the bars 1 and 2. The means for connecting the bars 42 and 43 and suspending them in place includes a U-shaped element 44 provided with oppositely disposed hook portions 45 at the top of the element which are hooked over the bars 1 and 2 as shown in Fig. 3. The bars 42 and 43 rest in curvatures 46 provided where the opposed side walls of

the element 44 join the horizontal lower portion of said element, and in order to secure the bars 42 and 43 to the element 44 a clamping member 47 is employed. The main portion of the clamping member 47 is extended parallel with respect to the lower portion of the element 44 and at the opposite end of this main portion the clamping member 47 is provided with curved bar-engaging portions 48. The clamping member 47 is drawn toward the lower portion of the element 44 by bolts 49 and as a result thereof the bars 42 and 43 are rigidly clamped between the curved portions 48 of the clamping member 47 and the curved portions 46 of the element 44.

The rearward portions of the bars 42 and 43 are connected together by a structure similar to the lower portion of the means made up of the element 44 and the clamping member 47; that is to say the structure for supporting the rear portions of the bars 42 and 43 comprises an element 50 and a clamping member 51 which are drawn into clamping engagement with the bars 42 and 43 by bolts 52. The supporting structure at the rear of bars 42 and 43 differs from the supporting means at the forward ends of said bars in that the element 50 and the clamping member 51 are provided with parallel upwardly inclined portions 53 to which eyes 54 are attached. The rear portions of bars 42 and 43 are supported by a rope 55 which is extended through the eyes 54 and is passed about the bars 1 and 2 in a suitable manner as shown in Fig. 4.

In arranging the improved apparatus in place for use the clamp 35 is applied to the conductor C at the proper point thereon, the wedge 39 of said clamp being drawn rearwardly relative to the body portion 36 of the clamp whereby said clamp very securely engages the conductor. As shown in Fig. 3 the conductor C extends through the notch 41 of the knob 40 of the clamp. The yoke 7 at this time has been secured to the pole P with the aid of the strap 14 and 16 as already explained herein. The apparatus A without the yoke 7 is drawn up the pole to a position where the forward portion of the apparatus is located above the conductor and with the member 29 disposed forwardly of the knob 40 of the wedge of the clamp 35. The forward end portion of the apparatus is lowered and the apparatus is then drawn rearwardly so that the knob 40 of the wedge of the clamp is disposed within the tapered opening 31 of the member 29 as shown in Fig. 5. When the device is ready for use the shanks of the bolts 5 and 6 extend through the openings 9 formed in the opposed end portions 8 of the yoke 7 with the ball bearing assemblies interposed between said opposed end portions of the yoke and the nuts 13 which are mounted on said bolt shanks. With the apparatus so arranged in place rotation of the nuts 13 in the proper direction will draw the entire apparatus, with the exception of the yoke 7, rearwardly, and because the apparatus is connected to the conductor C through the instrumentality of the member 29 and the knob 40 of the wedge of the clamp 35 pull will be imparted to the portion of the conductor located forwardly of the apparatus. This will put slack in the associated anchoring assembly made up of the insulators D and the clamp E whereby parts of said assembly may be removed and replaced as desired.

When slack is placed in the anchoring assembly associated with the conductor C the insulators sag to positions where they are supported by the associated bars 42 and 43. Also the bars

42 and 43 have associated therewith a member 56 which supports the clamp E when slack is put in the anchoring assembly, said member 56 being provided with opposed portions 56' which embrace the bars 42 and 43, as shown in Fig. 7, and a centrally located clamp-receiving portion 57. The opposed portions 56' which engage the bars 42 and 43 are held in engagement with said bars by pins 58.

To remove the apparatus from its operative position after work on an anchoring assembly has been completed the pins 10 are removed from their apertures in the opposed portions of the yoke 7. The shanks of the bolts 5 and 6 may then be moved outwardly out of the opening 9, the nuts 15 13 previously being unscrewed slightly. The forward portion of the apparatus is then moved forwardly to disengage the member 29 from the knob 40 of the clamp 35 after which the forward portion of the apparatus may be lowered to the ground, and the yoke 7 disengaged from the pole P.

The apparatus A in addition to being capable of use in a horizontal position, may be used in a vertical position as shown in Fig. 8. In that view 25 the yoke 7 is shown attached by means of the straps 14 and 16 to an arm F of a tower and the remainder of the apparatus hangs downwardly from said tower arm with the hooks 25 arranged in engagement with a conductor Ca. 30 With the apparatus so arranged manipulation of the nuts 13 in the proper direction will draw the portion of the apparatus other than the yoke 7 upwardly, thereby raising the conductor Ca and putting slack in the anchoring assembly G. 35

We claim:—

1. An apparatus for imposing pull on an electrical line to put slack in an anchoring assembly associated therewith, comprising a member mounted on a support, attaching means for preliminarily attaching said member to said support, a pair of spaced elongated elements arranged in parallelism, means for connecting said spaced elements together, a pair of means for adjustably connecting said spaced elements to said member, said pair of means comprising each a screwthreaded extension projecting from one of said spaced elements and extending through an opening formed in said member, and nuts on said screwthreaded extensions which on rotation thereof move said extensions and the elongated elements with which they are associated relative to said member, and means for connecting said spaced elements to an electrical line on which pull is to be imposed.

2. An apparatus for imposing pull on an electrical line to put slack in an anchoring assembly associated therewith, comprising a member mounted on a support, attaching means for securing said member to said support, said attaching means comprising a strap arranged to embrace said support, and a connecting element connected to said strap and to said member, a pair of spaced elongated elements arranged in parallelism, means for connecting said spaced elements together, a pair of means for adjustably connecting said spaced elements to said member, said pair of means comprising each a screwthreaded extension projecting from one of said spaced elements and extending through an opening formed in said member, and nuts on said screwthreaded extensions which on rotation thereof move said extensions and the elongated elements with which they are associated relative to said member, and means for connecting said spaced elements to an electrical line on which pull is to be imposed.

spaced elements to an electrical line on which pull is to be imposed.

3. An apparatus for imposing pull on an electrical line to put slack in an anchoring assembly associated therewith, comprising a member mounted on a support, attaching means for securing said member to said support, said attaching means comprising a strap arranged to embrace said support, a connecting element connected to said strap and to said member, and a spur removably carried by said member and adapted to be forced into the support, a pair of spaced elongated elements arranged in parallelism, means for connecting said spaced elements together, a pair of means for adjustably connecting said spaced elements to said member, said pair of means comprising each a screwthreaded extension projecting from one of said spaced elements and extending through an opening formed in said member, and nuts on said screwthreaded extensions which on rotation thereof move said extensions and the elongated elements with which they are associated relative to said member, and means for connecting said spaced elements to an electrical line on which pull is to be imposed.

4. An apparatus for imparting pull on an electrical line to put slack in an anchoring assembly associated therewith, comprising a member mounted on a support, a pair of spaced elongated elements arranged in substantial parallelism, a pair of means for adjustably connecting said spaced elements to said member, cross means for connecting said spaced elements together, said cross means including an inner element and clamping elements arranged in association with said inner element so as to clamp said spaced elements between said clamping elements and said inner element, an engaging member supported by said inner element, and wire-engaging means associated with an electrical line on which pull is to be imparted, said wire-engaging means being engaged by said engaging member.

5. An apparatus for imparting pull on an electrical line to put slack in an anchoring assembly associated therewith, comprising a member mounted on a support, a pair of spaced elongated elements arranged in substantial parallelism, a pair of means for adjustably connecting said spaced elements to said member, cross means for connecting said spaced elements together, said cross means comprising an inner element and clamping elements arranged in association with said inner element so as to clamp said spaced elements between said clamping elements and said inner element, and wire-engaging hooks associated with said clamping elements.

6. An apparatus for imparting pull on an electrical line to put slack in an anchoring assembly associated therewith, comprising a member mounted on a support, a pair of spaced elongated elements arranged in substantial parallelism, means for adjustably connecting said spaced elements to said member, cross means for connecting said spaced elements together, wire-engaging means associated with an electrical line on which pull is to be imparted, engaging means supported by said cross means for engaging said wire-engaging means, and a supporting structure suspended from said spaced elements and disposed therebelow.

7. An apparatus for imparting pull on an electrical line to put slack in an anchoring assembly associated therewith, comprising a member mounted on a support, a pair of spaced elongated

elements arranged in substantial parallelism, means for adjustably connecting said spaced elements to said member, cross means for connecting said spaced elements together, wire-engaging means associated with an electrical line on which pull is to be imparted, engaging means supported by said cross means for engaging said wire-engaging means, and a supporting structure suspended from said spaced elements and disposed therebelow, said supporting structure comprising a pair of elongated substantially parallel elements spaced apart a distance less than the spaced distance of the first mentioned spaced elements.

8. An apparatus for imparting pull on an electrical line to put slack in an anchoring assembly associated therewith, comprising a member mounted on a support, a pair of spaced elongated elements arranged in substantial parallelism, means for adjustably connecting said spaced elements to said member, cross means for connecting said spaced elements together, wire-engaging means associated with an electrical line on which pull is to be imparted, engaging means supported by said cross means for engaging said wire-engaging means, and a supporting structure suspended from said spaced elements and disposed therebelow, said supporting structure comprising a pair of elongated substantially parallel elements spaced apart a distance less than the spaced distance of the first mentioned spaced elements.

9. An apparatus for imparting pull on an electrical line to put slack in an anchoring assembly associated therewith, comprising a member mounted on a support, a pair of spaced elongated elements arranged in substantial parallelism, means for adjustably connecting said spaced elements to said member, cross means for connecting said spaced elements together, wire-engaging means associated with an electrical line on which pull is to be imparted, engaging means supported by said cross means for engaging said wire-engaging means, and a supporting structure suspended from said spaced elements and disposed therebelow, said supporting structure comprising a pair of elongated substantially parallel elements spaced apart a distance less than the spaced distance of the first mentioned spaced elements, and means adjacent to opposite ends of said supporting structure for attaching it to said first mentioned spaced elements.

10. An apparatus for imparting pull on an electrical line to put slack in an anchoring assembly associated therewith, comprising a member mounted on a support, a pair of spaced elongated elements arranged in substantial parallelism, means for adjustably connecting said spaced elements to said member, cross means for connecting said spaced elements together, wire-engaging means associated with an electrical line on which pull is to be imparted, engaging means supported by said cross means for engaging said wire-engaging means, and a supporting structure suspended from said spaced elements and disposed therebelow, said supporting structure comprising a pair of elongated substantially parallel elements spaced apart a distance less than the spaced distance of the first mentioned spaced elements,

and means adjacent to opposite ends of said supporting structure for attaching it to said first mentioned spaced elements, the attaching means at one end of the supporting structure comprising rigid means provided with hooks that engage said first-mentioned spaced elements and the at-

taching means at the opposite ends of the supporting structure including flexible means arranged in engagement with said first-mentioned spaced elements.
